UNITED STATES PATENT OFFICE.

PAUL KARL SCHWAB, OF NEW YORK, N. Y.

WINDOW-SASH.

SPECIFICATION forming part of Letters Patent No. 549,825, dated November 12, 1895.

Application filed December 8, 1893. Serial No. 493,169. (No model.)

To all whom it may concern:

Be it known that I, PAUL KARL SCHWAB, a citizen of the United States, residing at New York, in the county and State of New York, 5 have invented certain new and useful Improvements in Window-Sashes, of which the following is specification.

My invention relates to improvements in the class of window-sashes which are pivoted to swing in the window-frame in addition to the up-and-down sliding movement in the frame; and my invention consists of certain novel features in construction which will first be described in connection with the accompanying drawings and afterward particularly pointed out in the annexed claims.

Referring to the drawings, Figure I represents a front elevation of a window-frame having my improved window-sash supported therein. Fig. II is a front elevation showing the upper sash raised and swung open and the retaining-strips of the lower sash withdrawn. Fig. III is a front elevation showing both sashes raised and swung open. Fig. IV 25 is a vertical sectional view taken on the line 44, Fig. III. Fig. V is a detail sectional view showing the withdrawable retaining-strips in their normal position. Fig. VI is a detail sectional view showing the withdrawable retaining-strips as withdrawn and the window-sashes in position to be opened or tilted.

In said drawings, A represents a window-frame having a lower window-sash B and an upper window-sash C. These window-sashes 35 are each provided with the upper and lower cross-pieces D E, and on their vertical side rails are mounted the withdrawable retaining-strips or metal plates F, having horizontal slots f, through which extend pins G for 40 securing the plates to the side frames.

The pieces F may be provided with any suitable handle or handles, such as ribs S, extending the whole length of the strips at their inner edges, and are turned over at their upper ends, as shown, forming right-angled portions F', which rest on top of the window-sashes and project over the tops of the cord-stiles when they are projected, and thus materially assist in rendering the sashes airtight.

H and J are the cord-stiles operating in the customary ways in the window-frame A.

There are two cord-stiles H and two cord-stiles J, the lower sash B being pivotally supported between the stiles H by means of the 55 central pivot-pins K, while the upper sash C is pivotally supported between the stiles J by means of the central pivot-pins K'.

The cord-stiles H and J are of equal width with the window-sashes, and spaces are left 60 between the cord-stiles and the window-frame to provide vertical channels between the cord-stiles and the window-frame, into which the retaining-strips project.

M are parts or extensions hinged to the 65 stiles J at L, which enable the raising of the upper sash much higher by being folded over into the position shown in Figs. II, III, and IV. When the upper sash is closed, as in Fig. I, the parts M rest in the vertical ways 70 in the window-frame.

It will be observed that when the metal retaining-strips F are in the position shown in Fig. I, they will engage the window-frame and hold the sashes and allow them to move only 75 vertically, but when the strips are withdrawn, as shown in Fig. II, (lower sash,) the edges of the strips will be even with the edges of the sashes, and the sashes can be rotated on their pivots, as shown.

Having thus described my invention, the following is what I claim as new therein and desire to secure by Letters Patent:

1. The combination of a window frame, the cord stiles H and J working in the window frame and leaving spaces to form vertical channels between them and the retaining strips of the window frame, and the window sashes pivoted to the cord stiles H and J and adapted to slide vertically with them or swing 90 between them, provided with the withdrawable retaining strips F attached to the faces of the sashes and adapted to project into the channels between the faces of the stiles and the window frame and formed with transverse 95 slots f and longitudinal handle-ribs S extending the whole length of the strips along their inner edge, and the pins G engaging in the slots f and securing the strips F to the vertical parts of the window sashes, substantially 100 as set forth.

2. The combination of the window frame, the cord stiles H and J working in the window frame leaving vertical channels between

them, the window sashes pivoted to the stiles H and J, said stiles being of the same length as the window sashes, the withdrawable retaining strips F mounted on the faces of the 5 sashes in position to project into the channels between the stiles and window frame and formed with handle-ribs S extending the whole length of the strips, and right-angled portions F' resting on top of the sashes and adapted

to project over the tops of the cord stiles, and 10 suitable means for securing the retaining strips to the window sashes, substantially as set forth.

PAUL KARL SCHWAB.
